United States Patent Office

Des. 224,023

Patented June 27, 1972

224,023

PHONE DECORATION

Joyce G. Cliburn, 20201 Sherman Way,
Canoga Park, Calif. 91306

Filed Sept. 4, 1970, Ser. No. 24,835

Term of patent 14 years

Int. Cl. D14—03

U.S. Cl. D26—14

FIG. 1 is a perspective view of the phone decoration, showing my new design; and

FIG. 2 is a top plan view.

The broken lines are shown for illustrative purposes only.

I claim:

The ornamental design for a phone decoration, substantially as shown and described.
